CLAIM

We claim the ornamental design for a table leg for a display stand, as shown and described.

DESCRIPTION

FIG. 1 is a front perspective view of a table leg for a display stand showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a reference view thereof, in which a table leg for a display stand is applied; and,
FIG. 9 is a reference view thereof, showing a table leg for a display stand before assembling.
The broken lines in the figures show portions of a table leg for a display stand which are environmental structure and form no part of the claimed design.
